UNITED STATES PATENT OFFICE

CHARLES M. SCOTT, OF CARROLLTON, KENTUCKY

RADIO ANTENNA APPLIANCE

Application filed October 29, 1929. Serial No. 403,232.

This invention relates to a radio antenna device, and it is an object of the invention to provide an appliance of this kind which can be readily installed indoors and thus eliminating interference therewith from transmission power lines or telephone lines and also to afford protection against high winds and storms.

It is also an object of the invention to provide an appliance of this kind particularly adapted for indoor use and thereby avoiding the antenna wire serving as a conductor of lightning to the building.

Another object of the invention is to provide an appliance of this kind employing an antenna wire of sufficient gauge to operate a radio receiver to full capacity.

An additional object of the invention is to provide an appliance of this kind wherein the antenna wire is suspended on a plurality of insulation strips carried by the extremities of cross arms, the assembly being such to permit the appliance to be folded or compacted when not in use and when extended allowing the apparatus to be readily installed in an attic or in the upper room of a building.

A still further object of the invention is to provide an appliance of this kind embodying cross members or arms carrying insulation strips with which an antenna wire is directly engaged and wherein said insulation strips are arranged on angles of substantially seventy degrees with respect to the associated arms or cross members.

The invention consists in the details of construction and in the combination and arrangement of the several parts of my improved radio antenna device whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation of an

antenna appliance constructed in accordance with an embodiment of my invention and extended for use;

Figure 2 is a view partly in side elevation and partly in section of the structure as illustrated in Figure 1;

Figure 3 is a view in side elevation of the appliance as herein disclosed with the same in folded or compacted adjustment with the antenna wire omitted;

Figure 4 is a view in front elevation of the appliance as illustrated in Figure 3 with the antenna wire applied;

Figure 5 is a fragmentary sectional view illustrating the connection of an insulating strip with the extremity of one of the cross members;

Figure 6 is a fragmentary view in perspective of an end portion of one of the cross members.

As disclosed in the accompanying drawings, A and B denote two elongated members of wood or other desired material non-conductive of electricity. Each of these members, as herein set forth, is straight from end to end with the member B of a length less than the length of the member A to facilitate the folding or compacting of the appliance as will hereinafter be more particularly referred to.

Midway their ends the members A and B are provided with the notches or recesses 1 to provide means whereby the central portions of said members A and B may interlock when the members are disposed in substantially perpendicular relation one with respect to the other. Disposed through the portions of the members A and B provided with these notches 1 is an elongated headed shank 2, the head 3 of which coacting with the outer face of one of the members. The outer face of the second member has coacting therewith a holding nut 4 threaded upon the free end portion of the shank 2. The nut 4 is preferably of a wing type to effect the requisite manipulation thereof. The shank 2 is of a length to permit sufficient retrograde or outward movement of the nut 4 when it is desired to release the interfitting engagement between the members A and B in order

that said members may be folded or compacted as particularly illustrated in Figure 3 of the accompanying drawings.

Each extremity of the members A and B is reduced in thickness from one face thereof to provide a rabbet 5, the inner wall 6 of which being disposed transversely of the member on an angle of approximately seventy degrees and the outer edge face 7 of the member is in parallelism with the wall 6.

Coating with each end portion of the members A and B is an insulation strip 8 of desired length, said strip being of any preferred material and has its inner marginal portion strengthened by a reinforcing member 9 extending lengthwise of the strip 8 from end to end. This reinforcing member 9 is held to the strip 8 by screws 10 or the like coating with the opposite end portions of the strip 8 and member 9. The central portions of the strip 8 and member 9 are fitted within the rabbet 5 with the rear or inner edge faces thereof in direct contact with the wall 6 of the rabbet 5 whereby the strip 8, which is substantially straight from end to end, is held to the member A or B on an angle of approximately seventy degrees and also coplanar with the member.

As particularly illustrated in Figure 5, it is to be noted that the combined thicknesses of the strip 8 and member 9 are substantially equal to the depth of the rabbet 5 so that in the assembly the outer face of the strip 8 is substantially flush with the adjacent face of the member. The strip 8 is maintained in applied position with respect to the member, as herein disclosed, through the medium of a bolt 11 directed through the central portions of the strip 8 and member 9 and the adjacent end portion of the member. This bolt 11 has coating therewith in a conventional manner a nut 12.

In practice, my improved appliance is supported from a wall or the like with the long member A preferably disposed in a substantially vertical direction with, of course, the shorter member B horizontally disposed. The inner end portion of one insulating strip 8 has freely disposed therethrough a threaded shank 14 provided at one extremity with an eye member 15.

The shank 14 has threaded thereon a nut 16 for contact with the associated strip 8 upon the side face thereof remote from the eye member 15. Secured to the eye member 15 is an end portion of an antenna wire W. This wire as it leads from the eye member 15 is freely disposed in succession through the corresponding openings 17 provided in the outer longitudinal marginal portions of the strips 8 and spaced lengthwise therealong with the outer extremity of the wire W in electrical connection with a binding post 18, herein disclosed, as disposed through and carried by the lower end portion of the bottom

strip 8 of the member A. This post 18 is also adapted to have engaged therewith an antenna feed-in wire 19.

The upper end portion of the member A, as herein disclosed, has secured to its rear face at a desired point thereon an end portion of an elongated bracket arm 20. The outer portion of this arm 20 is offset with respect to the inner or connected end portion thereof a distance sufficient to position said outer end portion beyond the outer extremities of the strips 8 so that said outer end portion of the bracket arm may be secured to a wall or other desired support.

As clearly indicated in the accompanying drawings, it is to be noted that when my improved appliance is extended for use the strips 8 are disposed in convergence towards the center of the appliance so that the antenna wire associated with said strips results in the apparatus being in the general form of a pyramid. At this time it is to be stated that by having the member B of a length less than the length of the member A the folding or compacting of the appliance is facilitated and especially with the antenna wire W applied.

The wire W, except at its connected extremities, is freely disposed through the strips 8 so that said wire will offer no hindrance or obstruction to the desired folding or compacting of the appliance and by adjusting the nut 16 in proper direction pull may be imposed upon the wire W to tauten the same.

The appliance, as herein disclosed, is of a character to permit the same to be particularly advantageously used and its construction and assembly are such to allow it to be mounted within an attic or upper room of a building or any other relatively restricted places; while the folding features referred to are of especial advantage in the shipping or transporting of the appliance with the same in complete assembly.

This application is in continuation in part of application Serial No. 200,237 filed June 20, 1927.

From the foregoing description it is thought to be obvious that a radio antenna device constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A radio antenna appliance comprising

cross members in substantially perpendicular relation one with respect to the other, means for connecting said members one to the other, insulating strips carried by the opposite end 5 portions of the members and disposed on an angle with respect thereto, said insulating strips converging towards the center of the appliance, said insulating strips being provided with openings for the passage of an 10 antenna wire, one of the insulating strips having means for securing one end of the wire and for connecting a lead wire thereto, and means for engagement with the opposite end of the antenna wire and carried by one of the 15 insulating strips to tauten the antenna wire, said wire being positioned in superposed loops decreasing in size from the outermost loop with each loop disposed in a different plane.

2. A radio antenna appliance comprising 20 cross members in substantially perpendicular relation one with respect to the other, means for connecting said members one to the other, insulating strips carried by the opposite end portions of the members and disposed on an 25 angle with respect thereto, said insulating strips converging towards the center of the appliance, said insulating strips being provided with openings for the passage of an antenna wire, one of the insulating strips 30 having means for securing one end of the wire and for connecting a lead wire thereto, and means for engagement with the opposite end of the antenna wire and carried by one 35 of the insulating strips to tauten the antenna wire, each of said insulating strips being substantially coplanar with the member with which it is engaged, said wire being positioned in superposed loops decreasing in size from the outermost loop with each loop 40 disposed in a different plane.

3. A radio antenna appliance comprising cross members in substantially perpendicular relation one with respect to the other, means for connecting said members one to the other, insulating strips carried by the opposite end 45 portions of the members and disposed on an angle with respect thereto, said insulating strips converging towards the center of the appliance, said insulating strips being provided with openings for the passage of an antenna wire, one of the insulating strips having 50 means for securing one end of the wire and for connecting a lead wire thereto, means for engagement with the opposite end of the antenna wire and carried by one of the insulating strips to tauten the antenna wire, and a bracket arm secured to one of the members, the outer portion of said arm being offset to 55 position the same beyond the insulating strips, said wire being positioned in superposed loops 60 decreasing in size from the outermost loop with each loop disposed in a different plane.

In testimony whereof I hereunto affix my signature.

CHARLES M. SCOTT.
